UNITED STATES PATENT OFFICE.

CELESTIN POIROT, OF ERIE, PENNSYLVANIA.

SCREW-PLATE.

SPECIFICATION forming part of Letters Patent No. 567,408, dated September 8, 1896.

Application filed January 7, 1896. Serial No. 574,604. (No model.)

To all whom it may concern:

Be it known that I, CELESTIN POIROT, a citizen of the United States, residing at Erie, in the county of Erie and State of Pennsylvania, have invented certain new and useful Improvements in Screw-Plates; and I do hereby declare the following to be a full, clear, and exact description of the invention, such as will enable others skilled in the art to which it appertains to make and use the same.

This invention relates to screw-plates; and it consists in certain improvements in the construction thereof, as will be hereinafter fully described, and pointed out in the claim.

15 The invention is illustrated in the accompanying drawings, as follows:

Figure 1 shows a front elevation of the screw-plate, the face-plate being removed to better show construction. Fig. 2 shows a section on the line 2 2 in Figs. 1 and 3. Fig. 3 shows a section on the line 3 3 in Fig. 2.

A marks the stock, in the front face of which are grooves a , which form guides for the dies B. Immediately back of the guide-grooves the diameter of the stock is enlarged, forming a shoulder A^2 . Back of the shoulder A^2 the diameter of the stock is again reduced, and its periphery is provided with ratchet-teeth a^2 and notches a^3 . To the rear of the stock proper is attached what I term the "guide-stock" A', in the face of which are grooves a' , which form guides for the guide-pins B'. This guide-stock has a shoulder A^3 of the same diameter as the shoulder A^2 , the outer portion containing the groove a' being of substantially the same diameter as the outer part of the stock.

The outer ends of the dies have small extensions b , on which are shoulders b' . There is a cam-ring C, provided with cam-faces C^4 , one for each die. On the under sides of the cams are shoulders c , which engage the shoulders b' to draw the dies away from the center or away from the work, (the pipe F.)

45 The cam-ring is provided with a handle C', with which it can be turned to drive the dies to or from the work. It will be noticed that the cam-surface C^4 , that drives the dies to the work, acts upon nearly the entire width of the die, making a large wearing-surface, and as the force of the movement is exerted directly on the end of the die the die has no

tendency to tilt and so cause friction or binding in the die guide or grooves.

The dies and cam-ring are of such width 55 and thickness, respectively, as to come just flush with the surface of the stock, and a plate D is attached to the stock, holding them securely in place.

At the rear of the screw-plate the guide A', 60 the grooves a' , the guide-pins B', the extensions b' , the shoulders b^3 , the cam-ring C', having cam-faces C^5 , the cam-shoulder c , the handle C', and face-plate D' are shaped and arranged as are the stock A, the grooves a , 65 the dies B, the extensions b , the shoulders b^3 , the cam-ring C, having cam-faces C^4 , the cam-shoulder c , the handle C', and face-plate D, respectively, the guide-pins of course being blunt instead of having a cutting edge, as the 70 dies. The office of the guide-pins is to keep the screw-plate in line with the work, so that the dies will start properly.

Between the shoulders A^2 and A^3 , and journaled on the stock over the ratchet-teeth a^2 , 75 is the ratchet-ring E. Two handle-sockets E' extend from opposite sides of this ring, into which are placed the handles (not shown) for operating the plate. Two perforated lugs e on the ring E carry ratchet-pawls e' , which 80 are provided with stop-surfaces e^3 and a beveled or escapement surface e^2 . The pawls are round and are extended by a pin e^4 out of the lug e , and are provided with a milled thumb-cap e^5 . A spring e^6 is coiled around 85 the pin e^5 , the tension of which presses the pawl into engagement with the ratchet-teeth a^2 .

By reference to Fig. 3 it will be seen that if the ratchet-ring is turned to the right the 90 stock and dies will be carried with it, while in the return movement the beveled surfaces e^2 carry the pawls over the teeth, so that the stock remains stationary. By taking hold of the thumb-cap and pulling one of the pawls out and turning it around and then allowing it to return to position the ratchet-ring will be locked with the stock. By reversing both pawls we have a left-hand-ratchet screw-plate. The advantage of this arrangement 95 is obvious. Right or left thread dies may be used and the ratchet used in either instance.

What I claim as new is—

In a screw-plate, the combination of the

stock having the grooves *a* in its front face, the shoulder *A*² back of the grooved portion and the part back of the shoulder of less diameter than the shoulder and provided with
5 ratchet-teeth *a*²; the dies *B* within the grooves and having the extension *b* and shoulder *b'* thereon; the cam - ring *C* encircling the grooved portion with its front surface flush therewith and engaging the end of said die
10 and the shoulder *b'*; the plate *D* covering the grooved portion and the cam-ring; the

ratchet-ring journaled over the ratchet-surface back of the shoulder *A*²; and a ratchet-pawl in said ring operating on the ratchet-teeth of the stock.

15 In testimony whereof I affix my signature in presence of two witnesses.

CELESTIN POIROT.
